UNITED STATES PATENT OFFICE.

JUDGE N. SHOWS AND CLYDE B. TUCKER, OF PONCHATOULA, LOUISIANA.

NON-REFILLABLE BOTTLE.

1,108,012.

Specification of Letters Patent. Patented Aug. 18, 1914.

Application filed September 6, 1911, Serial No. 647,858. Renewed January 10, 1914. Serial No. 811,494.

To all whom it may concern:

Be it known that we, JUDGE N. SHOWS and CLYDE B. TUCKER, citizens of the United States, residing at Ponchatoula, in the parish of Tangipahoa and State of Louisiana, have invented new and useful Improvements in Non-Refillable Bottles, of which the following is a specification.

The present invention relates to certain novel and useful improvements in non-refillable bottles.

In carrying out our invention, it is our purpose to provide a non-refillable bottle which will embody in its construction the features of simplicity and efficiency and, furthermore, we aim to provide a bottle of the class referred to, which may be manufactured and marketed at a relatively low cost.

With the above-recited objects and others of a similar nature in view, the invention consists in the construction, combination and arrangement of parts, set forth in and falling within the scope of the appended claims.

In the accompanying drawing:—Figure 1 is a vertical longitudinal sectional view taken through the neck of a bottle, showing our improvements applied thereto. Fig. 2 is a similar view with the neck in inverted position. Fig. 3 is a perspective view of the lower sliding stopper. Fig. 4 is a similar view of the upper tubular stopper. Fig. 5 is a vertical longitudinal sectional view of a portion of the bottle neck containing a modified form of stopper.

Referring now to the accompanying drawings in detail, and especially to Figs. 1 to 4, inclusive, the letter A designates the neck portion of our improved bottle and extending upward from the shoulder of the neck is the tubular wall 1, said wall preferably projecting upward approximately one-third the length of the neck, although this may be varied if desired. Designed to slide within and seat upon the tubular member 1 is a sliding stopper 2 having a cylindrical body portion 3 formed with a curved channel 4 leading from the frusto-conical recessed bottom 5 of the body portion to the opening 6 in the side of the same and directly beneath the head 7 of the stopper, the head being adapted to contact with and rest upon the upper edge of the member 1. The head is provided centrally with a conical socket 8 adapted to receive and form a seat for the cone-shaped projection 9 formed on the bot-

tom of the upper tubular stopper 10, the latter comprising the enlarged body portion 11, and the goose-neck tube 12 formed integral therewith, the goose-neck passage 13 leading from the opening 14 in the base of the portion 11 to the outlet of the tube to permit the outflow of the liquid when the bottle is tilted or canted. This upper stopper 10 is cemented within the neck of the bottle, as shown at 15, the body of cement covering the sides of the portion 11 and preferably terminating at the point of junction of the goose-neck 12 with the body portion. It will also be noted that the upper stopper is cemented within the neck of the bottle a suitable distance above the tubular member 1 to permit the ready operation of the sliding stopper. If desired, the recess in the bottom of the sliding stopper may be weighted or loaded at the side walls thereof as at 16 to insure its positive operation in returning to its seat on the member 1.

From the above description, taken in connection with the accompanying drawings, the construction and operation of our non-refillable bottle, such as shown in its preferred form in Figs. 1 to 4, will be apparent. After the bottle has been filled with the liquid, the stopper 2 is dropped into position, and the stopper 10 cemented in the neck of the bottle, a suitable distance above the member 1. When the bottle is inverted to pour the liquid therefrom, the sliding stopper drops away into the position shown in Fig. 2, the flange leaving its seat on the member 1, and the conical recess in the top of the head receiving and seating the cone-shaped projection on the bottom of the stopper 10. The liquid will now flow from the bottle through the curved channel in the sliding or movable stopper thence through the goose-neck channel 13 and so out of the bottle through the top of the neck of the latter. Upon returning the bottle to upright position the sliding stopper will drop back upon the edge of the member 1, thus closing the opening 6 of the curved channel which will be below and surrounded by the upper portion of the tubular member.

In Fig. 5, we have shown a slightly modified form of our invention, in this case the lower stopper carrying a tubular socket 17 within which is seated a contraction spring 18, adapted to bear against the under side of the top stopper as at 19, while 20 design-

nates a tube adapted to telescope upon the tubular socket. When the bottle is inverted the weight of the liquor therein is sufficient to force the movable stopper outward 5 against the tension of the spring, but when the bottle is emptied the spring will force the lower or movable stopper into closing position.

It will be seen that we have provided a 10 simple form of non-refillable bottle comprising a movable stopper and a stationary stopper, each having suitable channels or passages therein and both so correlated and arranged that although the liquid may flow 15 freely from the bottle, the latter when once emptied can not be refilled.

We claim:—

1. The combination of a bottle having a tubular member formed in the neck thereof 20 and suitably spaced apart therefrom, a movable plug or stopper arranged within the tubular member and provided with a channel in the base thereof and opening onto the side, a second stopper mounted above the 25 first-mentioned stopper and rigidly secured to the bottle and spaced therefrom, said second stopper comprising a body portion, a curved extension connected to the body portion and forming a continuation of a 30 curved channel extending through the body portion, and means disposed intermediate said stoppers for holding the movable stopper spaced from the second stopper when the 35 bottle is inverted.
2. The combination of a bottle having a tubular member formed in the neck thereof and extending a short distance into the neck and coaxial with the said neck, a movable

stopper comprising a body portion adapted to extend into the tubular member and having a curved duct or channel extending from the bottom onto the side thereof, and a head portion designed to rest upon the tubular extension when the body is upright, a second stopper mounted above the first-mentioned stopper and spaced therefrom and having a goose neck passage therethrough, and means associated with the proximate surface of said stoppers and designed to hold the movable stopper spaced from the 50 stationary stopper when the bottle is inverted.

3. The combination of a bottle having a tubular member extending upwardly between the neck thereof, a movable stopper 55 adapted to slide in the neck portion and having a channel therein, the head portion of said stopper being formed with a socket, a second stopper mounted above the first-mentioned stopper and comprising a body 60 portion cemented in the neck of the bottle, and a curved tubular member communicating with a passage in the body portion, said body portion having a projection adapted when the bottle is inverted to seat within 65 the socket of the movable stopper to hold the movable stopper spaced from the stationary stopper.

In testimony whereof we affix our signatures in presence of two witnesses.

JUDGE N. SHOWS.
CLYDE B. TUCKER.
